US00D823913S

(12) **United States Design Patent** (10) Patent No.: **US D823,913 S**
(45) Date of Patent: ** Jul. 24, 2018

(54) **SEALER**

(71) Applicant: **Welcome Co., Ltd.**, New Taipei (TW)

(72) Inventors: **Ammy Chou**, New Taipei (TW);
Richard Chang, New Taipei (TW)

(73) Assignee: **WELCOME CO., LTD.**, New Taipei
(TW)

(**) Term: **15 Years**

(21) Appl. No.: **29/578,342**

(22) Filed: **Sep. 21, 2016**

(30) **Foreign Application Priority Data**

Apr. 18, 2016 (TW) 105302016

(51) **LOC (11) Cl.** **15-99**

(52) **U.S. Cl.**

USPC **D15/146**

(57) **CLAIM**

The ornamental design for a sealer, as shown and described.

DESCRIPTION

FIG. 1 is a top, front, and left perspective view of a sealer showing our new design;

FIG. 2 is a front side view thereof;

FIG. 3 is a rear side view thereof;

FIG. 4 is a left side view thereof;

FIG. 5 is a right side view thereof;

FIG. 6 is a top plan view thereof; and,

FIG. 7 is a bottom plan view thereof.

The broken lines showing portions of the sealer, form no part of the claimed design.

1 Claim, 4 Drawing Sheets
